UNITED STATES PATENT OFFICE.

VICTOR BREEZE, OF BRIGHTON, ENGLAND.

SWITCH FOR ELECTRIC CIRCUITS.

Application filed June 1, 1922. Serial No. 565,177.

To all whom it may concern:

Be it known that I, VICTOR BREEZE, a subject of the King of Great Britain, and resident of Brighton, in the county of Sussex, England, have invented certain new and useful Improvements in or Relating to Switches for Electric Circuits, of which the following is a specification.

This invention relates to electric switches more particularly of the push-button type, and has for its object to provide a switch of simple construction applicable for use with inductive currents and wherein the injurious effects of arcing are prevented or reduced to a minimum.

The present invention comprises an electric circuit switch having fixed and movable contacts, wherein the contacts are mounted in a tubular section of insulating material.

The open ends of the tubular section are preferably provided with covering plates consisting of sheets of insulating material.

Two embodiments of the invention as applied to a "start" and a "stop" switch respectively are illustrated by the accompanying drawings, wherein Figure 1 is a front elevation of a "start" switch having a removable cover, Figure 2 the same with the cover removed, Figure 3 an inverted sectional plan of the same, while Figure 4 is a front elevation of a "stop" switch, Figure 5 an inverted plan of the same, Figure 6 a sectional plan of the same, and Figure 7 a side section of the same.

In these drawings 2 is the tubular section of insulating material, 3, 3, the fixed stops or contacts and 4, 4 the movable stops or contacts. 7 and 8 are respectively the front and rear sheets of insulating material, 9 and 10 are respectively the front and rear portions of a casing, the portions being bolted together by screws and nuts 11.

The tubular section 2 of insulating material is of semi-circular shape designated to fit easily in the parts 9 and 10 of the casing and its lower portion is in the form of a diametrical wall adapted to rest at each side on ledges 12, 12 formed in the casing. The upper portion of the tubular section 1 is flattened at 13 to clear the screws 11, while the centre of its lower portion is trough-shaped to receive a bearing bracket 15 for a switch plunger 16, the bracket being fixed in the trough by a screw and nut 17. The bearing bracket 15 consists of a sheet of metal bent up and drilled to form a bearing

for the sliding plunger 16. The plunger 16 is provided at its front end with a push piece 18 of insulating material. In the rear end of the push piece 18 also bears one end of a spring 19 the other end thereof bearing against the upright portion of the bracket 15.

The inner end of the plunger 16 has affixed thereto a cross piece or bridge 20 on the ends of which are rotatively mounted contact stop rollers 4, 4, arranged in slots in the ends of the cross piece 20 and mounted on pins 21 of which the ends are secured to the cross piece at each side of the slot. The cross piece 20 is secured to the plunger 16 between washers 22 of insulating material.

The fixed contact rollers 3, 3 are rotatively mounted on pins 23 passing through the lower wall of the tubular section 2 of insulating material and securing thereto terminal blocks 24, 24, having screws 25, 25 for connecting thereto the ends of the leads. The ends of the leads are introduced through a cable carrying tube or boss screwed into the opening 26 provided in the bottom of the casing 10. The back of the casing 10 is provided with holes 27 whereby it can be fixed by screws to any suitable fixture. A boss 28 is provided in the front portion 9 of the casing in which the push piece 18 is arranged to slide freely.

It will be seen that the tubular section 2 extends into both the front and back portions 9 and 10 of the casing which hold it between the front and rear sheets 7 and 8 of insulating material. It will also be seen that as the insulating material is not secured to the walls of the casing, the tubular section in which the fixed and movable contacts are mounted independently can be removed completely from the casing with the tubular section, this is facilitated by the lead terminals on the outside of the tubular section being arranged to extend freely into a space provided in the lower portion of the casing.

In the "start" switch, the spring 19 is arranged to hold the movable contacts 4, 4 normally out of engagement with fixed contacts 3, 3, arranged behind them as in Figure 3, while in the "stop" switch the spring 19 is arranged to hold the movable contacts 4, 4 normally in engagement with fixed contacts 3, 3 arranged in front of them as in Figure 7.

In order to facilitate a slightly rotatable contacting action between the milled surfaces of the rollers 3, 3, and 4, 4, the distances apart of the centres of each pair is made sufficiently different to facilitate such rotary action.

What I claim and desire to secure by Letters Patent is:—

1. An electric circuit switch comprising fixed and movable contacts and circuit lead connecting terminals, an open ended section of a tube of insulating material, a divided casing consisting of two detachable tubular portions each open at one end and closed at the other and adapted when secured together with their open ends in contact to enclose and support in position the section of the tube of insulating material, the movable contacts being operatively supported independently of the casing by the sides of the section of the tube of insulating material and the lead connecting terminals extending through the sides of the tube of insulating material into the casing.
2. An electric circuit switch comprising fixed and movable contacts arranged in an open ended section of a tube of semi-circular cross section of insulating material, a casing for enclosing and supporting the tube of insulating material and provided at its inner sides with oppositely disposed supporting ledges and terminals for connecting the contacts to the circuit leads, the fixed contacts extending through the base of the tubular section of insulating material between the supporting ledges in the casing where they are provided with lead connecting terminals the supporting ledges also operating to support the tubular section in the casing and prevent it rotating therein.
3. An electric circuit switch having in combination, a laterally divided casing consisting of two tubular portions each open at one end and closed at the other and both detachably connected together with their open ends in contact, movable contacts operatively mounted on the sides of an open ended section of a tube of insulating material, associated circuit terminals leading to the contacts, loose plates of insulating material fitting against the open ends of the section and

detachably held thereon in the casing by the two portions.

4. An electric circuit switch comprising a casing, fixed and movable contacts operatively arranged within an open ended section of a tube of insulating material, associated circuit connecting terminals, the tube of insulating material being mounted in the casing, a spring returned movable contact operating plunger extending through an opening in the front of the casing and provided at its inner end with a pair of contacts having contacting surfaces consisting of the rims of rotatable wheels arranged to bridge the fixed contacts which also have contacting surfaces consisting of the rims of rotatable wheels.

5. An electric circuit switch comprising a casing, fixed and movable contacts operatively arranged within an open ended section of a tube of insulating material, associated circuit connecting terminals, the tube of insulating material being mounted in the casing, a spring returned movable contact operating plunger extending through an opening in the front of the casing and provided at its inner end with a pair of contacts having contacting surfaces consisting of the milled rims of rotatable wheels arranged to bridge the fixed contacts which also have contacting surfaces consisting of the milled rims of rotatable wheels.

6. An electric circuit switch comprising a casing, fixed and movable contacts operatively arranged within an open ended section of a tube of insulating material, associated circuit connecting terminals, the tube of insulating material being mounted in the casings, a spring returned movable contact operating plunger extending through an opening in the front of the casing and provided at its inner end with a pair of contacts having contacting surfaces consisting of the rims of rotatable wheels arranged to bridge the fixed contacts also having contacting surfaces consisting of the rims of rotatable wheels, the distance apart of the axes of wheels of the fixed and movable contacts being slightly different.

In witness whereof I affix my signature.
VICTOR BREEZE.
